UNITED STATES PATENT OFFICE.

PHILIPP L. F. METTMANN, OF NEW YORK, N. Y.

DESIGN FOR A POUSSE-CAFÉ DISPENSER.

49,155.

Specification for Design.

Patented June 6, 1916.

Application filed January 6, 1916. Serial No. 70,690. Term of patent 3½ years.

To all whom it may concern:

Be it known that I, PHILIPP L. F. METTMANN, a citizen of the United States of America, residing at 1016 Washington avenue, New York, in the county of Bronx and State of New York, have invented a new, original, and ornamental Design for Pousse-Café Dispensers, of which the following is a specification, reference being had to the accompanying drawing, forming part thereof.

The figure is a perspective view of a pousse café dispenser, showing my new design.

I claim—

The ornamental design for a pousse café dispenser, as shown.

PHILIPP L. F. METTMANN.
